US0D1022610S

(12) **United States Design Patent** (10) Patent No.: **US D1,022,610 S**
 (45) Date of Patent: ** Apr. 16, 2024

(54) **OIL STORAGE RACK FOR COOKING APPLIANCE**

(71) Applicant: **Kui Deng**, Chongqing (CN)

(72) Inventor: **Kui Deng**, Chongqing (CN)

(**) Term: **15 Years**

(21) Appl. No.: **35/514,464**

(22) Filed: **Jun. 1, 2022**

(80) **Hague Agreement Data**

Int. Filing Date: **Jun. 1, 2022**

Int. Reg. No.: **DM/221217**

Int. Reg. Date: **Jun. 1, 2022**

Int. Reg. Pub. Date: **Jun. 17, 2022**

(51) **LOC (14) Cl.** **07-09**

(52) **U.S. Cl.**

USPC **D7/602**

Primary Examiner — Brett Miller

(57) **CLAIM**

The ornamental design for an oil storage rack for cooking appliance, as shown and described.

DESCRIPTION

1. Oil storage rack for cooking appliance
1.1 : Perspective
1.2 : Front
1.3 : Back
1.4 : Left
1.5 : Right
1.6 : Top
1.7 : Bottom

1 Claim, 7 Drawing Sheets
